Wendell R. Holt, Los Angeles, Calif., assignor to Hughes
Aircraft Company, Culver City, Calif., a corporation
of Delaware

Filed Dec. 26, 1961, Ser. No. 68,063

Term of patent 14 years

(Cl. D57—1)

FIG. 3.

FIG. 4

FIG. 1 is a front perspective view of a monocular head-mounted cathode-ray tube viewer showing my new design, the wearer's head being for illustrative purposes only;

FIG. 2 is a top perspective view taken from the opposite side of FIG. 1;

FIG. 3 is a perspective view thereof taken from the right side of FIG. 1, with the wearer's head included as in FIG. 1; and

FIG. 4 is a rear perspective view thereof.

The dominant features of my design reside in the portions shown in full lines, the conventional cord element being fragmentarily shown for convenience of illustration.

I claim:

The ornamental design for a monocular head-mounted cathode-ray tube viewer as shown and described.
